UNITED STATES PATENT OFFICE.

FRANCIS EDWARD ROGERS AND EBENEZER HOSKING, OF MOUNT GAMBIER, SOUTH AUSTRALIA, AUSTRALIA.

SPARK-ARRESTER.

SPECIFICATION forming part of Letters Patent No. 739,225, dated September 15, 1903.

Application filed August 4, 1902. Serial No. 118,261. (No model.)

To all whom it may concern:

Be it known that we, FRANCIS EDWARD ROGERS and EBENEZER HOSKING, iron-workers, subjects of the King of Great Britain and Ireland, and residents of Commercial street, Mount Gambier, in the State of South Australia, Commonwealth of Australia, have invented a certain new and useful Spark-Arrester, of which the following is a specification.

The essential feature of the invention consists in the affixture of a rotatable screen within or below the funnel of a locomotive or other furnace and so situated and arranged as to be acted upon by the exhaust-current or by other power, such as a supplementary steam-jet. The screen may be of size and shape according to requirement of the particular funnel and furnace; but it is always of such shape and proportions that nothing can pass between its edges and the funnel, the whole of the steam and gaseous products of combustion passing through the leaves of the screen and the sparks being deflected back into the smoke-box. The screen may be either immediately within the base of the funnel or it may be placed slightly nearer the boiler. If within the funnel, the screen is of such size as to approximately fill the opening. When placed nearer the boiler, the screen is of larger size and so situated that the leaves in rotating approximately cover the opening of the funnel. In the latter case the funnel may be slightly widened at the bottom to afford room for the screen.

In order that our invention may be clearly understood, we will describe the same, with reference to the accompanying drawings, in which—

Figures 1, 2, and 3 illustrate a construction of screen which we have found satisfactory in operation. Fig. 1 is a side view, Fig. 2 a front view, and Fig. 3 a central vertical section. Figs. 4 and 5 show the screen in position within the base of the funnel. Figs. 6 and 7 show the screen placed somewhat below the funnel and nearer the mouths of the boiler-tubes.

In the construction illustrated, which we have found effective, the screen consists of four semicircular frames A, attached to a cen-

tral spindle C, with wire-netting D covering the space between the frames and the spindle, thus forming four leaves which radiate from the spindle. Each semicircular frame A consists, preferably, of angle iron or steel, and its ends are secured by bolts or rivets to two spiders B, mounted upon or attached to the central spindle C. The body of the leaf or the space between each frame and the spindle is filled by woven wire D of suitable mesh or a perforated plate. The outer edge of the woven wire is secured to the semicircular frame by clamps or rivets, while its edges at the center are all bound together and to the central spindle by a wire lace or in other convenient manner. The outer edge of each frame has a lip E projecting at slightly less than a right angle from the leaf. This may be produced by a suitable form of angle-iron or by a separate plate riveted thereto. This return-lip will project backward from the leaf when in operation.

In the screen shown in Figs. 6 and 7 the angle-iron frames are of semi-oval form; but otherwise the construction is the same. The spindle of the screen is supported horizontally by bearings H, one at each end, which are provided at any convenient position on the smoke-box or funnel and either inside or outside.

The exhaust or steam-jet pipe must be so situated or formed that the steam is directed toward one side of the screen, thereby causing it to rotate in the direction shown by the arrows in Figs. 4 and 6.

In operation when the exhaust or the operating steam-jet strikes against the leaf of the screen it turns it in the direction indicated and, striking the successive leaves, causes the screen to revolve rapidly. The result is that the sparks cannot pass the rapidly-revolving screen, because as they strike the leaves and the downwardly-projecting lips they are broken and thrown off the screen into the smoke-box and effectually prevented from entering the funnel.

It will be seen that there is no fixed screen or other obstruction to become choked, and thereby impede the current; but the axially-arranged screen being driven at a rapid rate the sparks are intercepted, broken up, and

thrown off the screen back into the smoke-box, while the steam and gaseous products of combustion pass through the leaves, and there is no reduction in the power and effectiveness 5 of the draft.

Having now particularly described and ascertained the nature of our said invention and in what manner the same is to be performed, we declare that what we claim is—

- 10. A spark-arrester, comprising a smoke-box provided with a cylindrical smoke-stack, an exhaust-nozzle mounted within said smoke-box and free to discharge into said smoke-stack, a revoluble member provided with 15 substantially semicircular screens radially mounted thereupon, said revoluble member being so disposed that said screens are free to successively obstruct the path of discharge

from said exhaust-nozzle into said smoke-stack, a semicircular lip mounted upon each 20 of said curved edges and projecting therefrom, the arrangement being such that said lips project from said curved edges and are successively directed toward said exhaust-nozzle for the double purpose of directing the 25 exhaust therefrom against said screens and of causing sparks to deflect against said screens.

In testimony that we claim the foregoing as our invention we have signed our names, in the presence of two witnesses, this 10th day 30 of June, 1902.

FRANCIS EDWARD ROGERS.
EBENEZER HOSKING.
